Attorneys.

UNITED STATES PATENT OFFICE.

WILLIAM HENRY PHELPS, OF INDIANAPOLIS, INDIANA.

APPARATUS FOR WASHING VEHICLES.

SPECIFICATION forming part of Letters Patent No. 579,242, dated March 23, 1897.

Application filed July 11, 1896. Serial No. 598,798. (No model.)

To all whom it may concern:

Be it known that I, WILLIAM HENRY PHELPS, a citizen of the United States, residing at Indianapolis, in the county of Marion and State of Indiana, have invented certain new and useful Improvements in Apparatus for Washing Vehicles; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to that class of apparatus designed to be used in washing vehicles of various kinds in a stable or carriage-house; and it consists more particularly of a novel swivel pipe-joint by which the hose for washing may be carried around the vehicle to gain the greatest advantage in time and labor and in use of the spray-nozzle.

The object of my invention is to provide means for swinging the water-pipe or hose around over the vehicle, following the operator, who carries the nozzle, and to provide such an apparatus that shall be free from the annoyances and expense incident to such appliances as heretofore used. In my device all leakage of water overhead is prevented, and it is cheaply manufactured, durable, and economical in use.

Referring to the drawings, Figure 1 represents a vertical section through a room arranged for washing a vehicle, showing my device in elevation situated below the ceiling. Fig. 2 is a top plan view, and Fig. 3 is a central sectional view, of the swivel-joint.

In the drawings, A designates my swivel-joint; B, a circular track which may be suitably supported by means of brackets to the ceiling. C is a carriage having rollers d supporting the outer end of a swinging pipe D, which has its outer end bent downward and to which, by means of a coupling a, the hose E, having a nozzle F, is attached. G designates a water-supply pipe suitably secured to the walls of the room and leading overhead to the center of the track B, where it may be suitably attached. At a convenient point in the supply-pipe is located and connected a valve

g, by which the water is admitted to the hose or shut off therefrom.

In constructing my swivel-joint I preferably use composition brass, but other suitable metals may be used, although those that are non-corrosive are best adapted. The part H has a nipple t, providing a passage Q, extending through the nipple, which is suitably threaded for connecting with the pipe G. In the recess at the larger end of the part H are screw-threads for receiving the threaded exterior of the cup-shaped part I, which has a recess f, and at the opposite or lower side a circular opening through the center, the inner edges of the central opening being ball-shaped to provide a seat for the outer surface of the swivel-piece K, the two parts fitting together in the form of a spherical joint M. On the outer end of the cup I is an annular groove m', in which is seated a spring J. The opposite end of the swivel-piece K has outside screw-threads over which is screwed the end l of an elbow L, having a circular flange P. A loosely-fitting collar N, having flange e, is mounted above the flange P, and has at its upper side an annular groove m, in which the opposite end of the spring J is seated. The under side of collar N and upper side of flange P has an annular groove in which are ball-bearings R. The elbow has a passage O through it. The opposite end may terminate in the pipe D, or may be suitably connected by means of threads i to a separately-formed pipe.

It will be seen that while the elbow carrying the swivel-piece and ball-bearings is rotated the spring rests in its upper bearings, and the ball-bearings and ball-joint M permits of rotation and flexibility of joint without leakage, the water-passage being continuous through the opening Q, f, h, and O to the hose.

In practical use the operator carries the nozzle F and in washing a vehicle carries it around to the various portions, drawing the hose E, which rotates the pipe-arm D, in the direction he is going, the supporting-carriage traveling around upon the circular track B, the swivel-joint A permitting the arm to rotate around the circle. It is obvious that in this way the hose is at all times out of the way overhead and entirely free from contact with

the vehicle, and when the work is completed the hose is swung around to one side, permitting the withdrawal of the vehicle from under without entailing the trouble of coiling and removing the hose, as is generally the case when drawn around upon the floor.

Having described my invention, what I claim as new, and desire to secure by Letters Patent, is—

- 10 o In an apparatus of the kind described, the combination of the swivel pipe-joint, comprising the part H, the cup-shaped part I connected thereto by means of screw-threads, the swivel part K having a ball-and-socket joint with said cup-shaped part I, the elbow

L having the flange P connected by screw-threads to the said swivel-piece, the collar N having an annular groove at upper and lower side, the spring J seated at each end in annular grooves in said piece I and in said collar N, and the ball-bearings R in grooves between said collar N and said flange P, substantially as shown and described. 20

In testimony whereof I affix my signature in presence of two witnesses.

WILLIAM HENRY PHELPS.
